W. F. HELMOND,
TYPE WRITING MACHINE,
APPLICATION FILED MAY 11, 1914

1,150,366.

Patented Aug. 17, 1915.

UNITED STATES PATENT OFFICE.

WILLIAM F. HELMOND, OF HARTFORD, CONNECTICUT, ASSIGNOR TO UNDERWOOD TYPEWRITER COMPANY, OF NEW YORK, N. Y., A CORPORATION OF DELAWARE.

TYPE-WRITING MACHINE.

1,150,366.

Specification of Letters Patent. Patented Aug. 17, 1915.

Application filed May 11, 1914. Serial No. 837,658.

To all whom it may concern:

Be it known that I, WILLIAM F. HELMOND, a citizen of the United States residing at Hartford, in the county of Hartford and State of Connecticut, have invented certain new and useful Improvements in Type-Writing Machines, of which the following is a specification.

My invention relates to improvements in typewriting machines, and an object of the invention is to provide an improved mechanism for permitting adjustment of the platen relatively to the line-space wheel, by which the platen may be easily released and adjusted, and then positively and reliably held in any position of adjustment.

The drawings show a clutch-drum loosely mounted on the platen axle and connected to the line-space wheel. Within said drum 20 is a disk, which, however, is fixed to the platen axle and carries a pair of curved grips or clutch arms to bear against the inner periphery of said drum. These arms spread or expand into gripping engagement 25 with the drum. This operation is performed by a pair of levers, or bell-crank, the ends of which extend between said arms. The ends of said levers may bear against a floating fulcrum pin, and knuckle-joint pins may 30 be interposed between said levers and the ends of the clutch arms, so that the devices are cheaply manufactured and readily assembled, and when the free ends of the levers are spread as by an operating cam 35 slidable longitudinally on the platen axle, the clutch members are spread into gripping engagement with the drum.

A spring-actuated detent lever, pivoted on the platen frame, is shiftable away from the line-space wheel by an operating cam lever, which may be positioned between the line-space wheel and the clutch drum and is journaled on the hub connecting said wheel and drum. The operating lever is rotatable 45 about the platen axle as an axis, to cam the detent away from the line-space wheel and cause the pressure of the detent spring to be transmitted through the operating lever to said hub and thereby apply a braking or 50 retarding action to the platen.

This invention is an improvement on the invention disclosed in my co-pending application, Serial No. 735,611.

Other features and advantages will appear hereinafter.

In the accompanying drawings, Figure 1 is a perspective view of the carriage and platen of an Underwood typewriting machine, with my invention applied thereto. Fig. 2 is a sectional end elevation view 60 showing the spring-operated detent for the line-space wheel, and the operating lever and brake. Fig. 3 is a sectional view of the clutch and associated parts. Fig. 4 is a perspective view of the invention with the 65 parts disassembled. Fig. 5 is a sectional elevation showing the clutch members in released position. Fig. 6 is a similar view with the clutch members in locking position. Fig. 7 is a detail view of the locking latch 70 for the clutch-operating cam. Fig. 8 is a view of the combined detent operating lever and brake. Fig. 9 is a detail view of the detent.

The rotary platen 1 is fixed to the axle 2 75 journaled in the platen frame 3 which is shiftable to upper and lower case positions in the traveling carriage 4. Line-space rotation of the platen is effected by the operation of a line-space lever 5 pivoted at 6 and 80 having an arm 7 to actuate a slide bar 8, to which is pivoted a pawl 9 coöperating with a line-space ratchet wheel 10 connected to the platen axle through the intermediary of clutch mechanism presently to be de- 85 scribed.

The clutch mechanism comprises a disk 11 having a hub or sleeve 12 fixed to the platen axle 2, as by means of a pin 13. A pair of clutch arms or grips 14 freely supported on 90 the front face of the disk 11, are adapted to be spread or expanded into frictional clutching engagement with the inner peripheral face of a clutch member 15 in the form of a drum or casing having a hub 16 mounted 95 to rotate freely on the hub 12 of the disk 11. The line-space wheel 10, is fixed to the hub 16 to rotate at all times with the clutch drum 15.

The lower ends of the clutch members 14 100 abut against a spacing block 17 secured to the disk 11 and expandable by means of a tapered screw 18, which enters a slot 19 in said block, permitting the bifurcated block to be spread by setting up said screw, thus 105 permitting an accurate and fine adjustment of the clutch members 14. The clutch members 14 are spread into gripping engagement with the clutch drum 15 by means of a pair of levers 20 fulcrumed on a floating fulcrum 110

pin 21 movable laterally to equalize the pressure on the clutch members 14, said pin 21 seated in notches 22 in the clutch members.

Interposed between the levers 20 and the arms 14 are knuckle-joint pins 23, which seat in recesses 24 in the said levers and arms. The levers 20 extend on opposite sides of the platen axle 2, and when they are in contact with the axle, as shown in Fig. 5, the clutch members 14 rest lightly against the drum 15, so that said drum, and with it the line-space wheel 10, are free to rotate relatively to the clutch members 14. The lower ends of the levers 20 are spread to effect a clutching engagement of the arms 14 with the drum 15 by means of a clutch operating cam 25. Said cam is mounted on the platen axle, and is slidable longitudinally of the axle, the inner end of the cam being tapered to enter between the axle and the clutch levers 20 to spread the latter to the Fig. 6 position, when the operating cam is moved inward.

It will be noted that the pins 23 are close to the fulcrum pin 21, and so positioned relatively to the fulcrum pin that only a slight movement of the arms 14 is effected, but a powerful leverage is obtained. This slight movement of the arms 14 is sufficient to cause them to powerfully grip the clutch drum 15 when said levers are spread, so as to positively prevent any relative rotation of the platen line-spaced wheel, but permitting free relative rotation of said parts when the levers 20 are moved inward to the Fig. 5 position. The pins 23 provide a cheaply constructed, efficient and practical form of knuckle-joint between the grips 14 and the levers 20, and aid in transmitting pressure from the levers 20 in a direction to distribute the pressure over the periphery of the drum 15. Viewed in another way, the pins act as wedges between the levers 20 and grips 14, and apply pressure to said grips in the direction of their length, as well as forcing the ends of the grips directly against the drum 15.

The grips 14 are preferably made of cast iron or other practically rigid or non-elastic material, to insure a positive action, but the levers 20 may be made of elastic material, as spring steel, permitting said levers to yield slightly when spread by the operating cam. The spring in the levers 20 insures an easy operation of the cam 25 and compensates for wear, unevenness or other variations, while insuring an effective gripping action of the said grips.

The cam 25 is operated by means of a button 26, to which are connected rods 27 and 28, extending through the hub 29 of a hand wheel 30 fixed on the platen axle, said rods slidable longitudinally in said hub, and at their inner ends having a lost motion connection with the cam 25. Said connection

is effected by heads 31 on said rods engaging behind an inwardly extending annular flange 32 on the enlarged hollow end or cup 33 formed on the cam 25. The heads 31 are formed on stems or reduced portions 34 of sufficient length to permit a limited longitudinal movement of the rods relative to the cam.

The clutch-operating cam 25 is adapted to be locked in operative position by a locking latch 35 (see Fig. 7), pivoted at 36 in a slot 37 formed in the hub 29. When the cam 25 is moved inward, the locking latch 35 is thrown inward by a spring 39 to a position behind the end of a rod 38 slidable in the hub 29 and connected at its forward end to the cam 25. Such connection may be formed by providing a neck on the rod 38 to receive the flange 32. When the latch 35 is in locking position it rests against a restricted portion 40 in the rod 27.

When the button 26 is pulled outward to release the clutch, the latch 35 is cammed outward by the rod 27 during the initial movement of said rod, while the lost motion between said rod and the cam 25 is being taken up. The rod 38 is thus released and permits the cam 25 to be withdrawn by the continued outward movement of the button 26, thereby releasing the arms 14 and permitting the platen to be rotated independently of the line-space wheel. The rods 27, 28 and 38 are held against accidental disconnection from the cam 25 by means of a spacing sleeve 40^a loose on the platen axle opposite the flange 32.

A cover plate 41 for the clutch drum 15 is spaced from the disk 11 by spacing blocks 42 and secured in position by screws 43 extending through the cover plate and threaded into the blocks 42. It will be noted that the clutch levers 20, arms 14, and the pins 23, 21, are all held in position within the clutch drum without being attached either to the drum or the disk 11.

The spring-operated detent for positioning and holding the line-space wheel 10 at line space intervals, comprises a roller 44 mounted on a pivot pin 45, on the outer end of an arm 46, the inner end of which is pivoted by a screw 47 to the platen frame. A spring 48 holds the detent roller normally against the line-space wheel. The detent may be thrown off the wheel by a lever 49 having an arc-shaped bearing 50, which rests against the hub 16 of the clutch drum, permitting the lever 49 to rotate about the platen axle 2 as a center. A cam 51 on the lever 49 enters a groove 52 in a roller 53 on the pivot pin 45. When the lever 49 is swung down to the Fig. 1 position, the detent roller is free to be held against the line-space wheel by the spring 48. When the lever 49 is swung upward by means of a handle 54 to the Fig. 2 position, the cam 51

throws the detent arm 46 away from the line-space wheel. The hub 50 of the lever 49 at the same time is pressed by the spring 48 against the hub 16, and thus produces a 5 braking pressure on the clutch form. The platen is thereby prevented from rotating too freely, thus permitting a quick and accurate rotary adjustment of the platen into position for making corrections or additions 10 of letters, interlined words, etc., and also preventing accidental displacement of the platen after such adjustment. The throw of the lever 49 is limited in both directions by the shoulders 55 at the ends of the cam 51.

15 It will be observed that the detent arm 46 holds the lever 49 against its bearing hub 16, preventing accidental displacement of said lever, which is seated between the line-space wheel and the clutch drum, thus obviating the necessity of any other supporting means for the lever, and permitting the latter to be readily placed in position or removed, by swinging the detent arm free from the said lever.

20 Variations may be resorted to within the scope of the invention, and portions of the improvements may be used without others.

Having thus described my invention, I claim:

30 1. The combination with a rotary platen and a line-space wheel, of clutch mechanism to connect the platen and said wheel comprising a member having an annular bearing surface, a pair of clutch members expandable into gripping engagement with said surface, a pair of clutch operating levers, and knuckle-joint pins interposed between said levers and said clutch members, to transmit and direct the operating force 40 applied to the clutch members.

2. The combination with a rotary platen and a line-space wheel, of clutch mechanism to connect the platen and said wheel comprising a member having an annular bearing surface, a pair of clutch members expandable into gripping engagement with said surface, a pair of clutch operating levers, knuckle-joint pins interposed between said levers and said clutch members, a floating fulcrum pin for said levers between said anti-friction rollers, and means to rotate 50 said levers about their fulcrum.

3. In a typewriting machine, the combination with a rotary platen and a line-space 55 wheel, of clutch mechanism to connect the platen and said wheel, said clutch mechanism comprising a clutch drum, a disk within the drum, expansion clutch members mounted on said disk, operating levers each having one end extending between the ends of said expansion members, knuckle-joint pins between said ends of the levers and the ends of the expansion members, and means to actuate said levers.

4. In a typewriting machine, the combination with a rotary platen and a line-space wheel, of clutch mechanism to connect the platen and said wheel, said clutch mechanism comprising a clutch drum, a disk within the drum, expansion clutch members 70 mounted on said disk, operating levers each having one end extending between the ends of said expansion members, knuckle-joint pins between said ends of the levers and the expansion members, a fulcrum pin between 75 said ends of the levers and forming a floating fulcrum for the levers, said levers extending on opposite sides of the platen axle, and an operating cam movable longitudinally of the axle into position to spread said 80 levers and thereby operate said expansion members into gripping engagement with the clutch drum.

5. In a typewriting machine, the combination with a rotary platen and a line-space 85 wheel, of a clutch mechanism to form a driving connection between the platen and wheel, said mechanism comprising a clutch member having an annular bearing surface, a pair of non-elastic clutch members having 90 bearing surfaces curved to conform to said annular bearing surface and having their ends spaced, a pair of operating levers extending between said spaced ends, and knuckle-joint pins, interposed between said 95 levers and the said ends of the clutch members, said levers operable to transmit pressure through said pins to the clutch members and cause their said bearing surfaces to grip the annular bearing surface. 100

6. In a typewriting machine, the combination with a rotary platen and a line-space wheel, of a clutch mechanism to form a driving connection between the platen and wheel, said mechanism comprising a clutch member 105 having an annular bearing surface, a pair of non-elastic clutch members curved to conform to said annular bearing surface and having their ends spaced to receive a pair of operating levers, knuckle-joint pins interposed between said levers and the said ends of the clutch members, said levers and clutch members formed with recesses to receive said knuckle-joint pins, and a fulcrum pin located between the ends of said levers adjacent the knuckle-joint pins and seated in recesses in the levers. 110

7. The combination with a rotary platen and a line-space wheel, of clutch mechanism forming a driving connection between said 115 parts, said mechanism comprising a clutch drum, a disk within said drum, a bearing block mounted on said disk, a pair of non-elastic clutch members each having one end abutting against said bearing block, a pair of operating levers extending between the ends of said clutch members opposite the bearing block, and means to actuate said levers and 120

thereby spread the said clutch members into gripping engagement with the inner periphery of the drum.

8. The combination with a rotary platen and a line-space wheel, of clutch mechanism forming a driving connection between said parts, said mechanism comprising a clutch drum, a disk within said drum, a bearing block mounted on said disk, a pair of non-elastic clutch members each having one end abutting against said bearing block, a pair of operating levers extending between the ends of said clutch members opposite the bearing block, means to actuate said levers and thereby spread the said clutch members into gripping engagement with the inner periphery of the drum, knuckle-joint pins between said levers and clutch members, and means to expand said bearing block to accurately adjust the clutch members.

9. The combination with a rotary platen and a line-space wheel, of clutch mechanism connecting the platen and wheel, comprising a clutch part having a circumferential friction holding surface, a grip extending along said surface, an operating lever, and a knuckle-joint pin between said lever and said grip to form a joint between the lever and grip through which an operating force may be transmitted to hold the grip against said surface.

10. The combination with a rotary platen and a line-space wheel, of clutch mechanism connecting the platen and wheel comprising a clutch part having a circumferential friction-holding surface, a grip extending along said surface, an operating lever, a knuckle-joint pin between said lever and said grip to form a joint between the lever and grip through which an operating force may be transmitted to hold the grip against said surface, and means to actuate said lever, said grip being formed of non-elastic material, said lever of spring material, whereby the grip is held against said surface with a yielding pressure.

11. The combination with a rotary platen and a line-space wheel, of clutch mechanism to connect the platen and line-space wheel, comprising a clutch part having a circumferential holding surface, a grip extending along said surface, means to form an abutment against which one end of the grip bears, an operating lever, and a knuckle-joint pin between said lever and the other end of said grip whereby a knuckle-joint is provided between the lever and grip through

which an operating force may be transmitted to the grip and cause the latter to grip said circumferential surface.

60

12. The combination with a rotary platen and a line-space wheel, of clutch mechanism connecting the platen and said wheel, comprising a clutch drum having an inner circumferential friction holding surface, grips within said drum having friction holding surfaces curved to conform to said circumferential surface and extending therealong, the ends of said grips being spaced, operating levers having portions projecting between said spaced ends, knuckle-joint pins between said ends of the grips and the levers, and seated in recesses in the grips and levers, means to actuate the levers and cause the grips to bear against the circumferential surface, and a cover plate or cap for said drum to prevent displacement of said grips, pins and levers.

65

70

75

13. The combination with a rotary platen and a line-space wheel, of clutch mechanism to connect the platen and said wheel, comprising a clutch part having a circumferential bearing surface, gripping means extending along said surface and having spaced ends, operating levers extending between said ends, means to actuate said levers, and knuckle-joint pins between said levers and said spaced ends, for transmitting and directing an operating pressure from the levers to said gripping means whereby the latter is caused to grip said circumferential surface.

80

85

90

14. The combination with a rotary platen and a line-space wheel, of clutch mechanism to connect the platen and said wheel, comprising a clutch part having a circumferential bearing surface, gripping means extending along said surface and having spaced ends, operating levers extending between said ends, means to actuate said levers, knuckle-joint pins between said levers and said spaced ends for transmitting and directing an operating pressure from the levers to said gripping means whereby the latter is caused to grip said circumferential surface, and a fulcrum pin between said levers forming a floating fulcrum for the levers whereby the pressure transmitted to the gripping means is equalized.
